UNITED STATES PATENT OFFICE.

WILHELM MESCH, OF MAGDEBURG, GERMANY, ASSIGNOR TO IDA MESCH, OF MAGDEBURG, GERMANY.

FLUSHING-TANK FOR WATER-CLOSETS.

1,186,414.

Specification of Letters Patent. Patented June 6, 1916.

Application filed April 14, 1915. Serial No. 21,234.

To all whom it may concern:

Be it known that I, WILHELM MESCH, architect, a subject of the King of Prussia, German Emperor, residing at 10 Blumenthalstrasse, Magdeburg, Germany, have invented new and useful Improvements in Flushing - Tanks for Water - Closets, of which the following is a specification.

This invention relates to siphon flushing cisterns for water-closets and the like and has for its object to provide alternatively a part or whole discharge of the tank merely by the well known traction of a chain at the lever fulcrumed on the walls 10 of the tank and connected to the top of the single hood or cup inverted over the discharge limb.

It consists in general in that the discharge pipe is divided in the height of the level 20 of the water to be retained after the part discharge; an upper part on the pipe prolonging the aforesaid pipe to the water-level of the whole filling or full discharge being connected to the cup or hood, and that an 25 air valve is provided in the cup admitting the air to the interior of the cup when in continuous lifting of the cup the water-level has sunk to the limb or margin of the lower part of the discharge pipe.

30 In the drawing Figure 1 is a vertical section through the tank and the flushing device therein, showing the ordinary ball cock supply valve or float operated valve for controlling the supply; the tank filled up. Fig. 35 2 the same section in which all means are in the position of partly discharging the tank.

a is the tank, *b* the supply valve, *c* the discharge pipe, the continuation *d* of which, 40 without the tank runs to the water-closet. The discharge pipe *c* within the tank projects about $\frac{2}{3}$ or $\frac{4}{5}$ of the ordinary length of discharge pipe; the wanting quarter or fifth of the length to let the tank be filled with 45 the usual quantity or height of water is formed by a short piece of tube *e*, guided axially on the discharge pipe. This tube *e* is connected, a certain distance from the top, to the hood so that, in the lowered position of the hood, the jointed discharge tube *c, e*, and the hood or inverted cup *f* show

nearly the same arrangement or position as the flushing apparatus in common use.

In the mantle of the hood *f* a valve is provided, represented in the drawing by a hole *g*, and a disk or plate *h* which is held in position and pressed to the hole *g* by a plate spring *i* secured to the discharge tube or the tank bottom. The hole in the mantle of the hood is provided in such a height, that in 60 lifting the hood the hole overcomes the upper margin of the lower discharge tube while the disk *h* remains and uncovers the hole.

The operation of the device is as follows: If 65 only a small flushing is desired the traction of the chain should be continuous; thereby the hood is lifted and with it the additional discharge tube *e*; the water flushes between the under margin of the tube *e* and the 70 upper margin of tube *c* through tube *a* to the closet, the water level sinks unto the limb of discharge tube *c* and unto the hole *g* in the mantle of the hood,—Fig. 2 of the drawing—and the here entering air destroys 75 the vacuum under the cup thus ceasing the action of the siphon. If full flushing is desired the traction must be short; thereby the water falls between both parts *e* and *c* of the discharge tube downward and by 80 immediately lowering the hood and with it the tube-piece *e*, the siphon begins to work over the upper margin of tube *e* in the well known manner and since hole *g* is then covered the cup or hood being in lowered position, the whole contents of the tank is 85 sucked out.

What I do claim and desire to secure by Letters Patent is:

1. In combination with the tank a discharge tube extending only to a height below the water level of the full filled tank, an additional tube guided on it extending to the water level, a hood over said discharge tubes connected to said additional 90 tube, a valve in the mantle of the hood and means for lifting and lowering the hood, substantially as set forth.

2. In combination with the tank a discharge tube, an additional tube, guides on 100 the additional tube engaging the discharge tube, a hood over said tubes and means for

fastening the additional tube to the hood, a hole in the mantle of the hood, a plate covering said hole, a plate spring connected to said plate and to the tank, and means for lifting and lowering said hood and its adjacent tube, substantially as set forth.

In testimony whereof I have signed my

name to this specification in the presence of two subscribing witnesses.

WILHELM MESCH.
